(57) CLAIM

(22) Filed: **Nov. 14, 2001**

The ornamental design for a tetrahedral fabric bag for use in fabric care processes, as shown and described.

DESCRIPTION

- (63) Continuation of application No. 29/120,518, filed on Mar. 20, 2000, now Pat. No. Des. 453,598.
- (51) **LOC (7) Cl.** **08-99**
- (52) **U.S. Cl.** **D32/35; D32/36**
- (58) **Field of Search** D32/37, 35, 36; 232/13, 43.2; 383/4, 13, 24, 71-75, 38, 39, 40, 34, 34.1, 97; 5/489, 490; D9/301

FIG. 1 is a front elevational view of a tetrahedral fabric bag for use in fabric care processes, embodying the new design, in its two-dimensional position;
